[57] CLAIM

The ornamental design for a vacuum cleaner, as shown and
described.

DESCRIPTION

FIG. 1 is front left perspective view of a vacuum cleaner
showing my new design;

FIG. 2 is front elevational view thereof;

FIG. 3 is a front right side perspective view thereof;

FIG. 4 is a rear right side bottom perspective view thereof;
and,

FIG. 5 is a rear left side perspective view thereof.

The surfaces or portions of the article not shown in the
drawings or described in the specification form no part of the
claimed design.
